METHOD AND MEANS FOR TRANSPORTING
LOGSAlbert M. Gilley, New Westminster, British
Columbia, Canada

Application July 10, 1936, Serial No. 89,990

7 Claims. (Cl. 214—152)

My invention relates to the art of coastal and seagoing transportation of logs.

Logs on the Pacific coast of North America are usually assembled into booms comprising from six or eight to twenty or twenty-five sections of logs, each containing approximately forty thousand feet per section. The logs are held between chained-together boom sticks overlaid with swifter sticks which are chained and secured to the chains that fasten the boom sticks together. These booms are towed long distances; on the Pacific coast tows of five hundred to a thousand miles are no uncommon events. Such booms however can only safely be towed during calm weather. If one of these large booms gets caught out in rough weather it is no uncommon thing for the tug to lose its tow through the logs jumping out and escaping from the boom proper. When this happens, great expense and delay are incurred because of the necessity of gathering up the logs and making up the booms again. It is to avoid the objectionable features of the above methods, now commonly employed, that is the primary object of the present invention.

Further, it is an object to provide a method and means by which deep-sea towing operations of logs may be carried on by the use of specially constructed scows and arranging the logs on the scows so that they will not come loose in rough weather, and so that they may be quickly and easily discharged or unloaded from the scow by the use of interlaced cables laid between the logs when the logs are being loaded.

A further object is to arrange the interlaced cables in the form of bridles, the ends of the bridles being anchored to the scow below the floor level thereof, the loop of the bridles being likewise anchored by means of eye-bolts, suitable means being provided for placing the bridles under tension.

Again, it is an object to provide a means for securing logs upon a scow in groups of logs so arranged that the logs of the several groups may be rolled off the scow one group at a time.

A further object is to provide for the bridle tighteners to act as auxiliary tighteners for the binding cables which hold the entire load in place on the deck of the scow.

Other objects of the invention will in part be obvious and in part be pointed out hereinafter.

To the attainment of the aforesaid objects and ends, the invention still further resides in the novel details of construction, combination and arrangement of parts, all of which will be first fully described in the following detailed description and then be particularly pointed out in the appended claims, reference being had to the accompanying drawing, in which:—

Figure 1 is a side elevation of a scow and logs

placed crosswise thereon, with the invention applied.

Figure 2 is a plan view of Figure 1.

Figure 3 is an enlarged detail perspective view, later again referred to.

In the drawing, which illustrates but one embodiment of the invention, 1 represents a scow of the usual construction to the sides of which, in suitable supports (brackets) 5, on pivot pins 4, are mounted chocks 2 and pulleys 3. The chocks are held projected above the deck of the scow by chains 9 anchored to eye plates 8 rigidly fastened, in any suitable way, to the sides of the scow, the chains being in sections connected by toggle hooks 10 so that the sections 9—9 of a chain may be separated when it is desired to drop the chock as when unloading the scow.

6 and 7 represent eye plates also suitably secured to the scow below the deck level, to which members 6 and 7 the ends of the bridles 18—18^a and 14—14^a are attached and to which the eye ends 21 and 16 of the tension hooks 19 and 15 are connected. The tension hooks 19 and 15 include turn-buckles 20 and 17, respectively, by means of which the bridles can be placed under tension.

The binding cables 11 pass around the pulleys or sheaves 13 and over the ends of the load, as best shown in Figure 1, a tensioning device comprising hook bolts 13—13, connected by a turn-buckle 12, being provided and located at any desired place in the length of the cable; for purposes of illustration the hooks 13—13 and turn-buckles 12 are shown located alongside the scow, although they might as well be located at the top of the load if desired.

As will be noted from Figure 1, the logs are laid to assume four groups, one composed of logs A being arranged in triangular form, a second group B being arranged in the form of a parallelogram along one side of the triangle, and the other two groups C and D being each arranged in the form of a parallelogram side by side along the other side of the triangle.

In loading the scow the bridles 14—14^a are laid along the deck of the scow, each to take in two groups A—B and C—D of the logs, respectively, while the bridles 18—18^a underlie only the outer groups B and D, respectively.

Both bridles 14—14^a pass upwardly between the groups A—C; the bridle 18 passes upwardly between the groups C—D; and the bridle 18^a passes upwardly between the groups A—B. The bridles are then passed over the top of the logs toward the opposite ends (opposite sides, if the logs are placed lengthwise) of the scow, where they connect to the hooks 15 and 19, respectively.

Before tightening the bridles the binding cables 11 are tightened up; then by tightening the

turn-buckles 17 and 20 the bridles will be drawn taut. This puts additional tension on the cables 11 and aids in securing the load in place.

When it is desired to unload the scow, the binding cable is slackened and released from the logs and the hooks 19-15 are unfastened; a suitable hauling line (not shown) is then hooked to the loop of the bridle 18, and, the chocks 2 having been first released, a pull on the hauling line 10 will cause the group of logs D to roll off the scow. The hauling line is then hooked to the loop of the bridle 14 and group C is rolled off. The turn-buckles 20 and 17 at the right of Figure 1 are loosened and the bridles 14a-18a 15 are unhooked, chocks 2 at the right are released, the haul line is hooked to the loop of bridle 18a and group B is rolled off. Then the haul line is hooked to bridle 14a and group A is rolled off.

20 Of course with scows on which logs are to be carried lengthwise eye plates 6x-7x (see Figure 3) will be mounted on the sides of the scow and a single closed-loop cable 11 may be used by passing it crosswise over the ends of the logs and 25 around under the pulleys. Other changes in the details of construction and arrangement of parts can be made by those skilled in the art without departing from the spirit of the invention or the scope of the appended claims.

30 What I claim is:

1. The method of transporting and unloading logs on scows which consists in laying the logs in tiers, arranging the logs in separate groups, providing each outer group with an independent 35 bridle anchored to the deck of the scow adjacent the edges thereof, providing the inner groups with similar bridles likewise anchored to the scow adjacent the same edges, binding the entire load of logs to the scow as a unit, then tensioning the bridles better to secure the load, and thereafter removing the binder and rolling off the groups of logs by pulling on the loops of the bridles.

2. The method of transporting and unloading 45 logs on scows which consists in laying the logs in tiers, arranging the logs in separate groups, providing each outer group with an independent bridle anchored to the deck of the scow adjacent the edges thereof, providing the inner groups 50 with similar bridles likewise anchored to the scow adjacent the same edges, binding the entire load of logs to the scow as a unit, then tensioning the bridles better to secure the load, and thereafter removing the binder and rolling off the groups of logs by pulling on the loops of the bridles one at a time.

3. In log-transportation, a conveying means having an unobstructed load supporting surface on which logs are piled in tiers, said logs being 60 arranged in groups, bridles anchored to the conveying means and embracing the respective groups, a binder cable engaging the conveying means and passing over all the logs to secure the logs to the conveying means, chocks on the conveying means at the sides of the log-pile, and means to apply tension through said bridles and logs to said binder cable.

4. In log-transportation, a conveying means having an unobstructed load supporting surface 70 releasable chocks extending above the deck level of the conveying means, releasable means to hold the chocks elevated, a pile of logs on the conveying means between said chocks, said pile

being divided into several groups of logs, bridles passing around the groups, means to anchor the bridles to the conveying means at the margins of the conveying means, adjustable tensioning means connecting the loops of the bridles to the conveying means at the said margins, and binding means passed over the pile of logs and connected to the conveying means for holding the logs together to the deck of the conveying means.

5. In log-transportation, a conveying means 10 having an unobstructed load supporting surface, releasable chocks extending above the deck level of the conveying means, releasable means to hold the chocks elevated, a pile of logs on the conveying means between said chocks, said pile being 15 divided into several groups of logs, bridles passing around the groups, means to anchor the bridles to the conveying means at the margins of the conveying means, adjustable tensioning means connecting the loops of the bridles 20 to the conveying means at the said margins, binding means passed over the pile of logs and connected to the conveying means for holding the logs together to the deck of the conveying means, and said binding means including a cable 25 with means to place it under tension.

6. In log-transportation, a conveying means having an unobstructed load supporting surface, releasable chocks extending above the deck level of the conveying means, releasable means to hold the chocks elevated, a pile of logs on the conveying means between said chocks, said pile being 30 divided into several groups of logs, bridles passing around the groups, means to anchor the bridles to the conveying means at the margins of the conveying means, adjustable tensioning means connecting the loops of the bridles 35 to the conveying means at the said margins, binding means passed over the pile of logs and connected to the conveying 40 means for holding the logs together to the deck of the conveying means, said groups of logs comprising a first group of triangular form in end elevation, and other groups of generally parallelogram-form in end elevation lying side by side 45 parallel to the sides of the first group, certain of said bridles embracing two groups and the others embracing but one group each.

7. In log-transportation, a conveying means having an unobstructed load supporting surface, releasable chocks extending above the deck level of the conveying means, releasable means to hold the chocks elevated, a pile of logs on the conveying means between said chocks, said pile being 50 divided into several groups of logs, bridles passing around the groups, means to anchor the bridles to the conveying means at the margins of the conveying means, adjustable tensioning means connecting the loops of the bridles to the conveying means at the said margins, binding 55 means passed over the pile of logs and connected to the conveying means for holding the logs together to the deck of the conveying means, and said binding means including a cable with means to place it under tension, said groups of logs comprising a first group of triangular form in end elevation, and other groups of generally parallelogram-form in end elevation lying side by side parallel to the sides of the first group, certain of said bridles embracing two groups and the others embracing but one group each.

ALBERT M. GILLEY.
